(57) CLAIM

The ornamental design for a holder for paper accessories, as shown and described.

DESCRIPTION

FIG. 1 is a front view of a holder for paper accessories in accordance with the new design;

FIG. 2 is a bottom view thereof;

FIG. 3 is a left side view thereof, the right side being a mirror image thereof;

FIG. 4 is a rear view thereof;

FIG. 5 is a top view thereof; and,

FIG. 6 is a front isometric view thereof.

The broken lines shown in FIGS. 1 and 3 to 6, which define the bounds of the claimed design, form no part thereof.

1 Claim, 3 Drawing Sheets

FIG. 1

FIG. 3

FIG. 2

FIG. 5

FIG. 4

FIG. 6
